UNITED STATES PATENT OFFICE.

WILLIAM H. JACKSON, JR., OF TRENTON, NEW JERSEY.

MACHINERY FOR ROLLING WIRE.

SPECIFICATION forming part of Letters Patent No. 298,977, dated May 20, 1884.

Application filed September 27, 1883. (No model.)

To all whom it may concern:

Be it known that I, WILLIAM H. JACKSON, Jr., of Trenton, in the county of Mercer and State of New Jersey, have invented new and 5 Improved Machinery for Rolling Wire, of which the following is a full, clear, and exact description.

In the ordinary process of making wire the series of grooved rollers used are placed end to 10 end, and the wire is passed from roller to roller in a tortuous course by attendants arranged on opposite sides of the rollers, and the wire is passed backward and forward through the grooves made in the rollers, which grooves 15 gradually diminish in size, so that the wire may be reduced to about three-sixteenths of an inch in diameter. Owing to the rapidity with which the wire cools when it reaches a small diameter, and the extent of wire necessarily exposed in 20 passing from roller to roller, and the slowness of the operation, it is impractical by the old process to roll the wire down to a less diameter than that mentioned, so that if smaller wire is desired, after reaching a diameter of about three- 25 sixteenths of an inch, the wire has to be removed from the rollers and reduced to the desired size by the well-known process of drawing, which is slow and expensive. Another disadvantage of the old process lies in the fact 30 that, besides having to have a man stationed at each bend in the wire for holding it out away from the rollers, two other men have to be employed for passing the end of the wire back and forth between the series of rollers. By 35 my new method I am able to practically roll wire down to a diameter of about one-eighth of an inch, thus saving the expense of drawing for that diameter of wire and much time and expense in the drawing process in making 40 smaller wire. I also save extra hands, there being required by my process only one man to each set of rollers.

My method consists in the construction and arrangement of parts, as will be hereinafter described and claimed.

Reference is to be had to the accompanying drawing, forming part of this specification, in which the figure shows, in section and side elevation, only the plant employed in carrying out

the new part of the process, it being deemed 50 unnecessary to show the old arrangement of rollers.

In carrying my invention into effect, I first pass the heated billet of iron, from which the wire is to be rolled, backward and forward in 55 the ordinary way between the ordinary rollers, until the billet is rolled down to a rod or wire of a quarter of an inch or less in diameter. Then I start one end of this rod or wire between the rollers A A', in the grooves a a', 60 made therein, and carry it thence to the similar grooves in the rollers B B', which grooves are smaller than those in rollers A A', thence to the grooves in rollers C C', thence through the furnace D, where the wire is heated, and then 65 on to the grooves made in the rollers E E', F F', and G G'. There may be as many sets of rollers in front of and beyond the furnace D as may be found necessary, and the grooves are made successively smaller in the different sets of 70 rollers, and the rollers are all kept in simultaneous operation, so that the wire will be carried rapidly along and made gradually smaller until reduced to the proper size, and instead of one furnace D there may be two 75 or more placed at proper intervals along the train of rollers, according to the length of wire to be made. The sets of rollers are journaled in suitable uprights, H H', and may be operated by any form of separate motor; but 80 I prefer to use the small steam-engines J, a separate engine being used for each set of rollers. These engines in this instance are attached to the uprights H, and are connected to the lower rollers, each by the connecting- 85 rod K, attached at one end to the piston-rod of the engine and at the other to the crank-wheel L, secured to the gudgeon or shaft of each of the lower rollers. The speed of each engine J is separately controllable by lever M 90 and rod O, that connects the lever with the valve-rod N. This is to enable the sets of rollers to be operated with variable speeds, so that the wire need not slack between the sets of rollers as it is gradually made smaller 95 and lengthened; and to give the attendants a still better control of the rollers I provide each lever M with a brake-shoe, P, which is adapted,

when lever M is depressed for cutting off the steam from the engine, to come upon the crank-wheel L, and thus serve as a brake to the rollers. After passing through the train of rollers, the wire will be reduced to a diameter of about one-eighth of an inch. If the wire is to be made smaller, it is then to be drawn to the required size by the ordinary drawing process.

It will be understood that the rolling process is much more rapid and much cheaper than the drawing process. The main advantage of my process over the old process therefore is that by my process it is practicable to reduce the wire by rolling much smaller than it can be done by the old process, thus avoiding much labor in drawing.

When a mill is to be built entirely on my plan, all of the sets of rollers will be arranged one in front of the other, and the billet from the start will be passed through them in a direct line; but when my system is applied to old mills, the billet will be passed backward and forward between the old rollers, as above described, and the situation of the furnace will vary according to that of the rollers.

Having thus described my invention, what I claim as new, and desire to secure by Letters Patent, is—

1. The combination, with a pair of wire-reducing rollers mounted in suitable uprights, and one of said rollers having a crank-wheel, L, of the engine J, above said rollers and connected with the crank-wheel by its piston and the connecting-rod K, and a lever, M, pivoted on the upright and connected to the valve-rod 35 N by rod O, substantially as set forth.

2. The combination, with a pair of wire-reducing rollers, of the engine J, the lever M, and brake-shoe P, the lever being connected to adapt it for cutting off steam to the engine, and at the same time for applying a brake to the wheel L, substantially as and for the purposes set forth.
